(57) **CLAIM**

I claim the ornamental design for an outsole for a shoe, as shown and described.

DESCRIPTION

FIG. 1 is a bottom perspective view of an outsole for a shoe showing my new design;

FIG. 2 is a bottom view thereof;

FIG. 3 is a right side view thereof;

FIG. 4 is a left side view thereof;

FIG. 5 is a front view thereof;

FIG. 6 is a rear view thereof;

FIG. 7 is a close up perspective view of the area indicated as 7 shown in FIG. 1; and,

FIG. 8 is a cross sectional view of the area taken along line 8—8 shown in FIG. 7, the broken outlines in FIGS. 7 & 8 along with the broken internal lines in FIG. 8 represent portions of the design that form no part of the claim.

The broken line around the indicia in the arch area of FIG. 1, along with the parallel broken lines around the peripheries of FIGS. 1 & 3-6, represent the boundaries of the design; with neither the lines themselves, nor the areas within them forming any part of the claim.
